UNITED STATES PATENT OFFICE.

EDWARD M. McNAMARA, OF CHICAGO, ILLINOIS.

MOP HOLDER AND WRINGER.

Application filed December 23, 1920, Serial No. 432,659. Renewed September 1, 1922. Serial No. 585,830.

To all whom it may concern:

Be it known that I, EDWARD M. McNAMARA, a citizen of the United States of America, and a resident of Chicago, in the county of Cook, State of Illinois, have invented certain new and useful Improvements in Mop Holders and Wringers, of which the following is a specification.

This invention relates to that type of household mop holders and wringers in which the wringing means is combined with the holding and manipulating means, and has for its objects:

To provide a structural formation and association of parts in the mop carrying frame whereby a strong and durable journal connection between the frame and the mop carrying drum is provided, and which in addition provides an effective attachment of the mop handle or stick to said frame.

To provide a structural formation imparting resiliency to the mop carrying drum and permitting a peripheral contraction of the same under excessive stress in a mop wringing operation to attain an effective squeezing action on the mop material.

To provide means for operatively connecting the operating lever to the drum in a substantial yet readily disconnectible manner, all as will hereinafter more fully appear. In the accompanying drawing:—

Fig. 1, is a front elevation of a mop frame and wringer embodying the preferred construction of the present invention.

Fig. 2, is a detail sectional end view of the same, with the mop material removed.

Fig. 3, is an end elevation, with parts broken away and with the mop material in its ordinary depending condition.

Fig. 4, is a companion view to Fig. 3, with the mop material in a wringing position on the carrying drum.

Fig. 5, is another companion view illustrating the mop material in a subsequent and partly released position in relation to the drum, for use in mopping confined places.

Fig. 6, is a detail cross-section of the drum.

Fig. 7, is a detail plan view of an end portion of the drum.

Fig. 8, is a front elevation of a modification embodying the application of the present improvement to a solid drum or roller.

Fig. 9, is an end elevation of the same.

Fig. 10, is a front elevation of another

modification illustrating a modified construction of the peripherally contractile drum.

Fig. 11, is an end elevation of the same. Like reference numerals indicate like parts in the several views.

Referring to the drawings, 1 designates the holding frame of the usual yoke shape and comprising a main longitudinal rail 2, a central socket member 3 adapted to receive the mop handle or stick 4, and end rings 5 in parallel relation. The rings 5 have a diameter corresponding to that of the mop drum or roller and are adapted to form bearings for the respective ends of said drum or roller.

In the construction illustrated in Figs. 1 and 3 the frame 1 is formed from a single bar or rod of metal of the required length, which is folded at the mid-length with the bend constituting the eye of the hereinafter described resilient latch piece 15. From said bend companion portions of the bar or rod extend to the center of the structure and are shaped into a pair of depending interspaced spirals to constitute the holding socket 3 for the tapering end of the mop stick or handle 4. From the lower ends of said spirals the portions of the bar or rod extend in opposite directions and in aligned relation to constitute the pressure bar 2 of the frame 1.

5 designate rings depending from the respective outer ends of the bar 2 to provide journal bearings for the hereinafter described revoluble mop drum, and 2' designate brace portions of the bar or rod extending diagonally towards the mop handle 4 to which they are attached to afford additional strength to the frame 1.

The described construction of the holding socket 3 affords an effective attachment for the end of the handle 4 such attachment being attained by turning the tapering end of the handle in the cavity of the spiral members to effect an expansion of the same, and an effective holding engagement of the parts.

6 designates the cylindrical mop drum or roller, which in the preferred form shown in Figs. 1 to 6 inclusive, is formed from an orificed sheet of metal bent into a cylindrical shell with the adjacent peripheral edges thereof in disconnected relation to provide an open space or gap, so that when undue stress is imposed on the periphery

of the drum during a mop wringing operation the cylinder will be capable of resilient contraction and in its tendency to return to its normal size will exert a very effective 5 squeezing action on the mop material.

7 designate out turned flanges or lips on the respective ends of the drum 6 for preventing endwise movement of the drum in the journal rings 5 of the frame 1, while 8 10 designate inturned flanges or lips at the ends of the drum to provide bearings or abutments for the operating handle herein-after described.

9 designates a longitudinal recess or depression formed in the periphery of the drum 6, and either of the concave form shown in Figs. 2, 3, 4, and 5, or the flat form shown in Fig. 9, as deemed most desirable. The purpose of the recess 9 is to 15 receive the fold of the mop material 10 at the point of operative connection to the drum, so that said fold may be in proper relation to the axis of the drum and attain an even rolling of the mop material around 20 the drum in a mop wringing operation.

The means for effecting a manual rotation is in many respects the same as shown and claimed in my companion application for Letters Patent Serial No. 432,658, and 30 comprises a member having a formation as follows:

11 designates a rod, which when in position, has parallel relation to the peripheral recess 9 of the drum 6, and adapted to receive the attaching fold of the mop material 10 to hold the same in proper operative connection with the drum.

12 designate angularly disposed extensions at the respective ends of the aforesaid 40 rod 11 and adapted to pass through slots and orifices in the circular wall of the drum 6, with the end of the extension 12 to the right in the drawing bent outwardly and passing inside the drum in operative position between the inturned lips 8 of the drum 45 above described, for connection to an operating lever member as follows:

13 designates an operating lever extending from the outwardly bent extension of 50 the aforesaid portion 12 to the right, and provided at its free end with an operating handle 13' for convenient manual rotation. Said lever is also provided with a prong 14 for engagement with the 55 resilient latch piece 15 theretofore described, so that with said parts in engagement the lever 13 is held against turning movement.

With the described construction an outward pull on the lever 13 will cause said 60 holding member to assume the position shown in dotted lines in Fig. 1, and permit of a ready removal and replacement of mop material 10 from and onto the rod portion 11 aforesaid.

65 The modified arrangement of parts illus-

trated in Figs. 8 and 9 is similar in some features to that set forth in my companion application Serial No. 432,658, with the angular extensions 12 of the operating means having operative engagement in diametric 70 channels formed in the respective ends of the drum or roller 6.

In the modified arrangement of parts illustrated in Figs. 10 and 11, the rod 11 of the drum operating member aforesaid has engagement in eyes 16 on one of the longitudinally curled edges of the wall of the drum 6, while the other longitudinally curled edge of said wall is provided with eyes 16' for a separate rod or section 11' 80 adapted to carry the mop material 10 as shown.

In the present mop structure the wringing or squeezing of the mop material 10 is effected by a revolution of the drum 6 to cause a winding of the mop material upon the perimeter of the drum and carry the mop material through the restricted throat or space between the perimeter of the drum and the longitudinal bar or rod portion 2 90 of the holding frame 1 to attain an effective compression or squeezing action upon the mop material. With a movement of the drum in a reverse direction the aforesaid portion 2 acts to retard the mop material so that the squeezed portion of the same will bank up and become loosened as illustrated in Fig. 5, ready for a mopping operation in confined places.

Having thus fully described my said invention what I claim as new and desire to secure by Letters Patent is:—

1. In a mop holder and wringer, the combination of a revoluble drum, a frame having bearing rings at its ends of an internal 105 diameter equal to that of the drum adapted to encircle and provide peripheral bearings for the ends of the drum, means for preventing longitudinal movement of the drum in the bearing rings, means for attaching the 110 mop material to the drum, and means for imparting rotation to the drum.

2. In a mop holder and wringer, the combination of a revoluble drum, a frame having bearing rings at its ends of an internal 115 diameter equal to that of the drum adapted to encircle and provide peripheral bearings for the ends of the drum, means for preventing longitudinal movement of the drum in the bearing rings, means for attaching the 120 mop material to the drum, the same comprising a longitudinally extending rod having engagement at its respective ends with the drum, and means for imparting rotation to the drum.

3. In a mop holder and wringer, the combination of a revoluble drum, a frame having bearing rings at its ends of an internal 125 diameter equal to that of the drum adapted to encircle and provide peripheral bearings

for the ends of the drum, said drum having out turned stop flanges at its ends for abutment against the bearing rings to prevent independent movement between the parts,

5 means for attaching the mop material to the drum; and means for imparting rotation to the drum.

4. In a mop holder and wringer, the combination of a revoluble drum, a frame 10 formed of rod metal shaped to provide a longitudinally extending rail having bearing rings at its respective ends and a central spiral tapering socket, the said bearing rings being formed to encircle and provide 15 peripheral bearings for the ends of the drum, means for attaching the mop material to the drum, and means for imparting rotation to the drum.

5. In a mop holder and wringer, the combination of a revoluble drum, a frame 20 formed of rod metal shaped to provide a longitudinally extending rail having diagonal side braces, bearing rings at its respective ends and a central spiral tapering socket, 25 the said bearing rings being formed to encircle and provide peripheral bearings for the ends of the drum, means for attaching the mop material to the drum, and means for imparting rotation to the drum.

30 6. In a mop holder and wringer, the combination of a revoluble drum, a frame having bearing rings at its ends adapted to encircle and provide peripheral bearings for the ends of the drum, a longitudinal rod 35 adapted to support the mop material and having angular extensions at its ends for engagement with the circular shell of the drum, and an operating lever for the drum attached to one of said extensions.

40 7. In a mop holder and wringer, the combination of a revoluble drum, a frame having bearing rings at its ends adapted to encircle and provide peripheral bearings for the ends of the drum, a longitudinal rod 45 adapted to support the mop material and having angular extensions at its ends for

engagement with the circular shell of the drum, an operating lever attached to one of said extensions, and a latch member mounted on the frame and adapted to engage said lever. 50

8. In a mop holder and wringer, the combination of a revoluble drum, a frame having bearing rings at its ends adapted to encircle and provide peripheral bearings for 55 the ends of the drum, a longitudinal rod adapted to support the mop material and having angular extensions at its ends for engagement with an orifice in one end of the shell of the drum and in an orifice in an 60 inturned flange at the other end of said shell, and an operating lever attached to one of said extensions.

9. In a mop holder and wringer, the combination of a main frame carrying a pressure bar, a hollow drum of flexible material journaled in said frame parallel to and adjacent said pressure bar, means for attaching mop material to the drum, means for rotating the drum, said drum being formed with a longitudinal gap along its entire 65 length adapted to permit yielding contraction of the drum when the mop material is wound upon the drum to wring the same. 70

10. In a mop holder and wringer, the combination of a main frame, carrying a pressure bar and end bearing rings, a hollow drum of flexible material journaled in said bearing rings parallel to and adjacent said pressure bar and having out turned flanges 80 at its ends engaging against said bearing rings, means for attaching mop material to the drum, means for rotating the drum, said drum being formed with a longitudinal gap along its entire length adapted to permit 85 yielding contraction of the drum when the mop material is wound upon the drum to wring the same.

Signed at Chicago, Illinois, this 18th day of December 1920.

EDWARD M. McNAMARA.
